Primary Examiner—Wallace R. Burke*Assistant Examiner*—Robin V. Taylor*Attorney, Agent, or Firm*—Evenson, McKeown, Edwards and Lenahan**[57] CLAIM**

The ornamental design for a forklift, as shown and described.

DESCRIPTION

FIG. 1 is a right side view of a forklift showing my new design;

FIG. 2 is a left side view thereof;

FIG. 3 is a rear end view thereof;

FIG. 4 is a front view thereof;

FIG. 5 is a left, front perspective view thereof; and,

FIG. 6 is a top, left perspective view thereof.

The broken line showing is for illustrative purposes only and forms no part of the claimed design.

FIG. 1

FIG. 2

FIG. 3

FIG. 4

FIG. 5

FIG. 6
